UNITED STATES PATENT OFFICE.

WILLIAM E. MOORE, OF PITTSBURGH, PENNSYLVANIA.

COTTON GINNING AND CLEANING.

1,136,969.

Specification of Letters Patent. Patented Apr. 27, 1915

Application filed April 16, 1908. Serial No. 427,413.

To all whom it may concern:

Be it known that I, WILLIAM E. MOORE, a citizen of the United States, residing at Pittsburgh, in the county of Allegheny and State of Pennsylvania, have invented certain new and useful Improvements in Cotton Ginning and Cleaning, of which the following is a specification.

This invention relates to the ginning and cleaning of cotton or other fibrous material, and the principal objects of the said invention are, first, to improve the ginning proper by providing for the doffing of the gin saws by air in such manner as to increase the cleanliness of the cotton and to diminish the energy usually necessary in air-doffing gins; and, second, to provide improved means for the cleaning of the cotton between the time that it leaves the gin and the time that it reaches the condenser.

Other objects of the said invention will more fully appear from the following description in which reference will be had to the accompanying drawings forming a part 25 of this specification and wherein,

Figure 1, represents in top plan and partly in section combined ginning and cleaning apparatus embodying my said invention; Fig. 2, a vertical fragmentary sectional view of a gin constructed according to my invention; Fig. 3, an enlarged detail fragmentary perspective view showing the constricted gin saw doffing air passages; Fig. 4, an enlarged fragmentary section taken on line 4—4 Fig. 2 looking to the right; Fig. 5, a cross-section of the cleaner taken on line 5—5 Fig. 6 looking to the right, and Fig. 6, a vertical longitudinal section of said cleaner taken on line 6—6 Fig. 5 looking to 40 the right.

Referring first to the construction of my improved gin proper, this comprises, among other parts, a roll box 1 of any suitable construction in which are mounted the gin saws 2 and ribs 3, which also may be of the usual or any suitable construction.

For the purpose of doffing the lint cotton from the saws, I provide an air doffing arrangement of peculiar construction. This 50 consists, in the case shown, of an air inlet flue 4 having its mouth 5 opening through the gin frame to the outside air and having a constricted throat 6 provided with a series of slots 7 through which extend the gin saws 55 to the interior of the throat. The throat 6 is gradually constricted from its upper por-

tion to the doffing point 8 when it gradually gets larger and merges into an outlet flue 9 of greatly increased area over the restricted throat, the latter flue passing through the 80 gin frame to the outside. By means of this construction I produce a Venturi-tube effect, which produces an extremely high velocity of air at the doffing point with a comparatively small expenditure of power. 65 The velocity of the air at the doffing point may be increased by further constricting the passage of air in the throat 6 at the doffing point. For this purpose I provide a series of air obstructing devices which, in 70 the present case, are shown as blocks 10 of oval cross-section which are inserted as shown in the throat 6 between the saws, with their sides substantially parallel to the direction of the air currents, the said blocks 75 being spaced far enough apart to permit of free rotation of the saws. The large air passage 4 tapering to a passage or throat of greatly decreased area at the doffing point, then expanding into a passage of relatively greatly increased area produces the 80 maximum doffing effect with the minimum expenditure of power at the exhaust and also allows the gin to "mote" properly.

In practice the gin saws pull through the gin ribs a considerable amount of trash and dirt which would naturally have a tendency to pass through the slots 7 and thence into the exhaust tube 9, mixing with the cotton therein. In order to avoid this, the 90 gin is provided with a chamber 11 extending transversely across the gin and having air inlet passage 12 between the top wall 13 thereof and the top of the flue 4. By connecting this chamber to an exhaust fan as 95 through an opening 14, a suction may be created in the chamber 11 which will draw into said chamber through passage 12 most of the dirt which is drawn through the ribs by the saws. In Fig. 1, 15 represents such an exhaust fan connected to the chambers 11, 11 of the two gins 16 and 17, through ducts 18 and 19.

20 is merely an outlet from the fan 15 for the air and dirt from ducts 18 and 19. 205

Fig. 1 also shows these gins connected up for operation in connection with my improved cotton cleaning system, in which 21 and 22 represent exhaust flues leading from the exhaust doffing flues 9 of the respective gins to an inlet pipe 23 of a cotton cleaning device 24. This latter device com-

prises, in the case shown, among other parts, a drum casing 25 in which is mounted a cylindrical screen 26 of wire mesh or other suitable open work structure extending the entire length of the said drum. This cylindrical screen has an inlet opening 27 registering with an inlet pipe 28, is closed at one end 28 by the head of the casing 25 and opens at its other end into the chamber of an exhauster 29 in the casing of which is mounted a fan 30 on a shaft 31 which extends axially through the cylindrical screen 26, being mounted at its ends in suitable bearings. Mounted fast on this shaft within the screen 26 are a plurality of spiders 32, which carry bars 33 adapted to be rotated by said shaft in close proximity to the inner wall of the screen 26. Rotary motion may be imparted to shaft 31 through pulley 34 from any desired source. The screen 26 being in the form of a complete cylinder, the cotton is given one or more revolutions in a spiral path as it goes longitudinally through said screen. The bottom of the casing 25 forms a hopper 35 provided at its bottom with an outlet 36. The exhauster outlet 37 is connected through any suitable duct 38 with a condenser 39 of any desired construction. In practice the fan of the exhauster 29 is rotated so as to create an air current passing into the gins at the inlet flue 4, thence past the gin saws, through flues 21 and 22, to the cleaner, to the fan of the exhauster 29, from which part onward to the condenser the air becomes a forced blast in contradistinction to an exhaust. By means of this air current the cotton is first doffed from the gin saws, then transported to the cleaner where it passes into the screen 26. Here it is beaten by the rotary bars 33, the dirt passing downward through the screen to the outlet 36. The cotton is then sucked through longitudinally of the screen 26 into the exhauster 29 where it is then forced along to the condenser. Under ordinary circumstances the single fan 30 unless very large and rotated at an extraordinary speed would not be sufficient to do all this work, but owing to the arrangement of the air flues at the doffing points, herein described, the necessary power to effect the doffing is greatly reduced. This arrangement also makes it possible to make the lint flues from the gins to the cleaner and from the cleaner to the condenser much smaller therefore at a lower cost. Moreover, as the exhauster is much more positive in its operation than the air currents induced by the ordinary gin brush cylinder, there is a decidedly less tendency in my apparatus for the lint flues to choke. My invention also makes it possible to use a much smaller condenser with less screen area than is ordinarily used. Furthermore, my improved

method of air handling the exclusion from the lint cotton of dust and dirt from the gin saws, the thorough cleaning to which the lint is subjected between the gin and the condenser, all greatly improve the quality of the cotton staple.

Having thus described a form of my invention, what I claim is:

1. A gin for cotton or the like, comprising in combination with the gin saws, an air doffing flue comprising a Venturi tube having an inlet of relatively large area tapering to a constricted throat at the doffing point and then expanding gradually into an outlet passage of relatively large area.

2. A gin for cotton or the like, comprising a gin frame, gin saws mounted therein, and an air doffing flue having a constricted throat provided with a series of slots into which extend the respective gin saws.

3. A gin for cotton and the like, comprising a gin frame, gin saws mounted therein, and an air doffing flue having a curved or bent neck in which is formed a constricted throat provided with a series of slots into which extend the respective gin saws.

4. The combination with a gin frame, of gin saws mounted therein, an air doffing flue having a relatively expanded mouth and a constricted throat provided with a series of slots into which extend the respective gin saws, the said flue expanding in area from said throat toward its outlet end, and means to create an air suction entering at said mouth and passing said saws to the outlet.

5. A gin for cotton and the like, comprising a gin frame, gin saws mounted therein, an air doffing flue having a constricted throat provided with a series of slots into which extend the respective gin saws, and air obstructing bodies mounted in said constricted throat between the respective gin saws, for the purpose set forth.

6. A gin for cotton and the like, comprising a gin frame, gin saws mounted therein, an air doffing flue having a constricted throat provided with a series of slots into which extend the respective gin saws, and air obstructing means comprising bodies substantially oval in cross-section mounted substantially as herein described in said constricted throat between the respective saws, for the purpose specified.

7. A gin for cotton and the like, comprising a gin frame, gin saws mounted therein, an air doffing flue comprising a Venturi tube into the constricted throat of which said saws extend, a chamber located above said flue and having an opening located near the point where said saws pass into said flue and means to create an air suction through said opening into said chamber, substantially as described.

8. A gin for cotton and the like, comprising a gin frame, gin saws mounted therein,

an air doffing flue tapering to a restricted throat at the doffing point and then gradually expanding to form a Venturi tube, the teeth of said gin saws extending into the restricted throat of said flue, a chamber located above said flue and having an opening located near the point where said saws pass into said flue, substantially as described.

10 9. The combination with a cotton gin provided with an air doffing flue tapering to a constricted neck at the doffing point and expanding into an enlarged outlet to form a Venturi tube, of a cotton cleaner provided 15 with an exhaust fan, and a duct leading from said doffing flue to the said cleaner, the said exhaust fan being arranged to create a suction from the doffing point of the gin saws through said cleaner.

20 10. The combination with a cotton gin, of a duct to convey the ginned cotton away from the said gin, cotton cleaning mechanism arranged to receive the cotton from said duct, an exhaust connected to said mechanism, a condenser, the said exhaust being arranged to create an air suction or exhaust from said gin through said duct and cleaning mechanism and a blast from the exhaust to the condenser, by which the 25 30 cotton is drawn by suction from the said gin to said exhaust and blown from said exhaust to the condenser.

11. The combination with a cotton gin provided with an air doffing flue in proximity to the gin saws, of a duct connected to the outlet end of said flue to convey the ginned cotton away from the said gin, cotton cleaning mechanism arranged to receive the cotton from said duct, an exhaust connected to said mechanism, a condenser, a duct leading from said exhaust to said condenser, the said exhaust being arranged to create an air suction or exhaust from a point beyond the doffing point of the gin 40 45 50 saws through said duct and cleaning mechanism and a blast from the exhaust to the condenser, by which the cotton is doffed and drawn by suction from the said gin to said exhaust and blown from said exhaust to the condenser.

12. The combination with a cotton gin provided with an air doffing flue having a constricted throat into which the gin saws extend, of a duct connected to the outlet end 55 60 65 of said flue to convey the ginned cotton away from the said gin, cotton cleaning mechanism arranged to receive the cotton from said duct, an exhaust connected to said mechanism, a condenser, a duct leading from said exhaust to the condenser, the said exhaust being arranged to create an air suction from a point beyond the doffing point of the gin saws through said duct and cleaning mechanism, and a blast from 70 75 80 85 85 the exhaust to the condenser, by which

the cotton is doffed and drawn by suction from the said gin to said exhaust and blown from said exhaust to the condenser.

13. The combination with a cotton gin constructed and arranged to have the cotton doffed from its saws by air, of a duct provided with a constricted throat at the doffing point of the gin saws and adapted to convey the ginned cotton away from said gin, cotton cleaning mechanism to receive 75 80 85 90 95 said cotton from said duct, and a fan blower in series with said parts to create an air suction to doff the gin saws, and to convey the doffed cotton through said duct and through cotton cleaning mechanism.

14. The combination with a cotton gin constructed and arranged to have the cotton doffed from its saws by air, of a duct provided with a constricted throat at the doffing point of the gin saws and adapted to 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 into the restricted neck of which extend the gin saws.

19. A cotton gin employing suction currents for removing cotton from the saws, comprising a series of saws, an intake air duct having an opening adjacent the teeth of said saws, and of diminishing cross-sectional area toward and adjacent said opening, and an outtake air duct having an intake opening also adjacent the teeth of said saws and adapted to receive suction air currents from said intake duct in a direction from the base toward the point of said saw teeth.

20. A cotton gin employing suction currents for removing cotton from the saws, comprising a series of saws, an intake air duct having an opening adjacent the teeth of said saws, and of diminishing cross-sectional area toward and adjacent said opening, and an outtake air duct having an intake opening also adjacent the teeth of said saws and adapted to receive suction air cur-

rents from said intake duct in a direction from the base toward the point of said saw teeth, the said saws projecting into the portion of said intake duct of diminishing cross-sectional area.

21. A gin for cotton and the like, comprising in combination with the gin saws, an air doffing flue having an inlet of relatively large area tapering to a contracted throat and then tapering into an outlet passage of relatively large area, the said flue having openings for the saws arranged to permit the teeth of the saws to enter said flue on the air intake side of said throat where the flue is of larger area than at its throat and pass out of said flue at a point within said throat.

In testimony whereof I affix my signature in presence of two witnesses.

WILLIAM E. MOORE.
